UNITED STATES PATENT OFFICE.

ROY J. MYARS, OF SAN DIEGO, CALIFORNIA.

DESIGN FOR A FRONT FENDER.

47,340.

Specification for Design.

Patented May 11, 1915.

Application filed December 29, 1914. Serial No. 879,607. Term of patent 7 years.

To all whom it may concern:

Be it known that I, ROY J. MYARS, a citizen of the United States, residing at San Diego, in the county of San Diego and State of California, have invented a new, original, and ornamental Design for Front Fenders, of which the following is a specification, reference being had to the accompanying drawings, forming a part thereof.

Figure 1 is a perspective view illustrating

the design of my fender; Fig. 2 is a front elevation.

I claim:

The ornamental design for a front fender, as shown.

ROY J. MYARS.

Witnesses:

MATTIE M. THOMAS,
ROBERT F. THOMAS.
